(57) **CLAIM**

The ornamental design for a stool, as shown and described.

DESCRIPTION

FIG. 1 is a top, front, perspective view of a stool showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom, front, left perspective view thereof;

FIG. 9 is a bottom, front perspective view thereof;

FIG. 10 is a bottom, rear perspective view thereof; and,
FIG. 11 is a partial cross-sectional view taken through line
11-11 of FIG. 6 thereof.

The broken lines showing the underside handles represent unclaimed subject matter. The broken line circular regions on the bottom of the stool form no part of the claimed design.

1 Claim, 11 Drawing Sheets
